AIR PRESSURE GAUGE FOR AUTOMOBILE
WHEELS

Ralph E. Manning and Guy K. Standen, Miami,
Fla., assignors of one-fourth to Lewis C. Eaker,
one-fourth to W. F. Gillette, and one-fourth to
F. S. Cassidy, and one-fourth to said Manning,
all of Miami, Fla.

Application November 14, 1938, Serial No. 240,394

1 Claim. (Cl. 201—48)

This invention relates to new and useful improvements in means for indicating to automobile drivers the air pressure condition of the wheels of the vehicle.

The principal object of the present invention is to provide indicating means for installation on the usual instrument board of the vehicle adapted to indicate to the driver the exact pressure of the air in the vehicle supporting wheels of the automobile, to the end that the vehicle will not be operated on under-inflated tires.

Other objects and advantages of the invention will become apparent to the reader of the following specification.

In the drawing:

The figure shows a fragmentary detailed sectional view through the wheel switch means.

Referring to the drawing, wherein like numerals designate like parts, it can be seen that a fitting 14 protrudes through an opening 15 from the annulus 16, and extends into the inflated pneumatic tube 17, interposed between the said annulus 16 and the annulus 18, the annulus 18 having a flange portion 19 which interlaps with the stationary annulus 16. These two annular members 16 and 18 are concaved at their opposed sides to conform with the normal curvature of the inflatable tube 17. Numeral 20 represents a case which is flanged as at 21 and bolted as at 22 to the inner side of the brake housing 23. The case 20 is provided with skirt portion 23a through which projects the rods 24, these rods projecting rigidly from the annulus 18 and being bolted or otherwise secured as at 25 to the ring 26 against which the transversely curved roller 26a is operative. This roller is rotatably mounted within the yoke 27 at the lower portion of the arm 28 which is rockably supported as at 29 and has its upper portion operating through the upper portion 30 in the stationary wall 31 of the brake housing and in the box 32 of the rheostat unit generally referred to by numeral 33. In this unit 33 is the resistance unit 34 against which the contact head 35 at the upper end of the arm 28 rides. A spring 36 between the upper portion of the arm 28 and the box 32 serves to constant pull the lower end of the arm toward the ring 26.

Adjusting screws 37 are provided on the case 20 and between the outer eye ends of these screws and the eyes 38 on the ring 26 are the springs 39.

A binding post 40 is provided on the box 32 and this is connected as at 41 to the resistance 55

unit 34, and is connected to an indicating instrument (not shown).

It can now be seen that in the event the air pressure in the wheel tube 17 drops, the inflation 5 of the small inflatable tube 17 will drop, allowing the springs 39 to pull the ring 26 in an outward direction with the result that the roller 26a following the ring 26 will allow the arm 28 to swing upwardly and move its contact 35 along 10 the resistance element 34 thus effecting a visible change on the indicating instrument (not shown).

As can be seen in the drawing a vent 20a is provided in the case 20 for the purpose of preventing 15 the occurrence of air pressure between the case 20 and the annulus 18 from interfering with the free movement of said annulus 18.

Obviously, the apparatus aforescribed can be used not only on and in conjunction with 20 the pneumatic wheels of land vehicles but also in connection with the pneumatic wheels of aircraft, and furthermore this indicating apparatus can also be used in conjunction with dual wheels.

While the foregoing specification sets forth the 25 invention in specific terms, it is to be understood that numerous changes in the shape, size and materials may be resorted to without departing from the spirit and scope of the invention as claimed hereinafter.

Having described the invention, what is claimed as new is:

A tire condition indicator control for pneumatic wheels comprising a wheel, an annular skirted casing carried thereby and rotatable therewith, 35 a fixed annular channeled member in said casing, a second annular channeled member adjustably mounted in said casing for overlapping relation with respect to said first mentioned channeled member, a pneumatic tube disposed between 40 said channeled members having an air connection with the customary tire casing inner tube, a plurality of pins extending through the skirted casing in contact with the adjustably mounted channeled member, a ring secured to 45 and supported by the inner ends of said pins, resilient tensioning means exteriorly disposed about the skirt portion of said casing connecting the same to said ring, a rheostat carried by the wheel in fixed position, and a rockable rheostat contact arm having a roller at its inner end in riding engagement with said ring to effect variations in the rheostat setting due to variations in tube pressure.
